UNITED STATES PATENT OFFICE.

JAMES D. JOYCE, OF PHILADELPHIA, PENNSYLVANIA.

BOBBIN.

Application filed June 4, 1921. Serial No. 474,961.

To all whom it may concern:

Be it known that I, JAMES D. JOYCE, citizen of the United States, residing at Philadelphia, in the State of Pennsylvania, have 5 invented certain new and useful Improvements in Bobbins, of which the following is a specification.

This invention relates to bobbins designed for holding yarn of various kinds and sizes, 10 the object in view being to produce economically a bobbin which will hold the smoothest yarn in such manner as to prevent the same from creeping upwardly or longitudinally of the stem of the bobbin, either during 15 the process of winding the bobbin or during the operation of unwinding the bobbin, permitting the yarn to have a much freer ballooning or unwinding action during the knitting operation, which, as is well 20 known, is a very desirable feature. In some cases the yarn has more or less moisture content during the winding operation and is apt to become loose in the package as the 25 yarn dries out after the winding operation is completed. Under the present invention the yarn is held more effectively on the bobbin, even after becoming thoroughly dried out.

With the above and other objects in view, 30 the invention consists in the novel construction and arrangement herein fully described, illustrated and claimed.

In the accompanying drawings:

Figure 1 is a side elevation of the im- 35 proved bobbin;

Figure 2 is a diametrical section through the same;

Figure 3 is a cross-section on the line 3—3 of Figure 2, taken through the metal sheath- 40 ing of the bobbin.

The improved bobbin comprises a base 1 which is generally cone-shaped and formed with a multiplicity of annular steps 2, which serve to prevent slippage of the yarn during 45 the winding of the preliminary layers thereon. The bobbin, which is ordinarily of wood, also comprises a stem 3 of any desired length according to the completed size of the bobbin; and the bobbin further comprises a 50 central longitudinal bore 4 to receive the spindle of the winding machine, the base 1 of the bobbin being countersunk to form a key-receiving recess 5 in the bottom thereof, which recess receives a correspondingly 55 shaped projection on the winding machine, thereby insuring the driving rotation of the

bobbin as a whole during the winding of the yarn thereon. The upper extremity of the stem is rounded or convex, as shown at 6.

In carrying out the present invention I 60 make use of a suitable length of tubing, preferably of thin sheet metal, forming a sheathing 7 which surrounds, encases and covers the bobbin stem. The sheathing 7 is swaged outwardly along spiral lines to form 65 outwardly embossed and projecting hollow yarn supporting ribs 8 of substantial size in cross-section, each of said ribs extending approximately half-way around the sheathing and stem of the bobbin, as illustrated in the 70 drawings, and terminating short of the top and bottom ends of the sheathing, as clearly shown. The upper end portion of the sheathing is spun or peened inwardly, as shown at 9, so as to conform to and fit the 75 corresponding rounded or convex upper extremity of the bobbin stem. Finally the sheathing is fixedly secured to the stem of the bobbin by forming said sheathing with indentations or swaging the same inwardly, 80 preferably at diametrically opposite points, as shown at 10, until portions of the metal are partially imbedded in the stem of the bobbin. This prevents any relative rotative or longitudinal movement of the sheathing with 85 respect to the bobbin stem, the sheathing being thereby fixedly secured to the bobbin.

From the foregoing description, taken in conjunction with the accompanying drawings, it will now be understood that as the 90 yarn is wound around the sheathed portion of the bobbin stem, said yarn will rest at least two points in each wrapping thereof upon the spirally disposed raised ribs, and will also bear against the intervening 95 smooth portions of the sheathing. As a result of this, the yarn will be prevented from slipping around or longitudinally of the bobbin stem and will be found a particularly desirable feature in case the yarn is wound 100 upon the bobbin in a moist condition. The bobbin will hold the smoothest yarn from creeping upwardly on the stem thereof, either during the process of winding the 105 yarn thereon, or in case the yarn dries out after the winding operation has been completed.

The bobbin is of special assistance in knitting operations, as the yarn will not bind upon the bobbin, but rides upon the 110 sides and ridges thereof, enabling the same to unwind or balloon with much greater

freedom than is the case with the ordinary bobbin. The spiral ridges or ribs are of ample size in cross-section and rounded in such manner as to avoid any tendency to 5 chafe or injure the yarn wound thereon.

Having thus fully described the invention, what is claimed is:

In a bobbin, the combination with a bob-

bin stem, of a sheathing tube fitted closely around the same and swaged outwardly 10 along a plurality of spiral lines to form steeply pitched ribs each extending less than the full circumference of the tube.

In testimony whereof I have affixed my signature.

JAMES D. JOYCE.
